(57) **CLAIM**

The ornamental design for a ride-on power trowel, as shown and described.

DESCRIPTION

FIG. 1 is a front elevation view of the ride-on power trowel showing our new design;

FIG. 2 is a right side view thereof;

FIG. 3 is a back elevation view thereof;

FIG. 4 is a top plan view thereof;

FIG. 5 is a left side view thereof;

FIG. 6 is a bottom plan view thereof;

FIG. 7 is a top, front, right side isometric view thereof;

FIG. 8 is a top, front, right side isometric view of the nose piece portion of the ride-on power trowel shown removed for ease of illustration;

FIG. 9 is a top front view thereof;

FIG. 10 is a right side view thereof;

FIG. 11 is a back view thereof;

FIG. 12 is a top plan view thereof;

FIG. 13 is a left side view thereof;

FIG. 14 is a bottom plan view thereof;

FIG. 15 is a bottom, front, right side isometric view thereof;

FIG. 16 is a right side view of one of the side gratings portion of the ride-on power trowel shown removed for ease of illustration;

FIG. 17 is a front, right side isometric view thereof;

FIG. 18 is a top, front, right side isometric view of the frame member portion of the ride-on power trowel shown removed for ease of illustration;

FIG. 19 is a back, bottom, left side isometric view of the fuel tank portion of the ride-on power trowel shown removed for ease of illustration;

FIG. 20 is a top, front, right side isometric view thereof;

FIG. 21 is a front elevation view of the ride-on power trowel shown in open condition; and,

FIG. 22 is a top back, right side isometric view thereof.
